UNITED STATES PATENT OFFICE.

LESTER KYLE ALDRICH, OF SIDNEY, OHIO.

AUTOMATIC FEEDER.

Application filed February 23, 1926. Serial No. 89,875.

The invention relates to an automatic feeder for sheet material.

The object of the present invention is to improve the construction of automatic feeders for sheet material or especially the automatic feeder shown and described in Patent No. 1,546,184, granted to me July 14, 1925, and to increase the pick-up area of the suction nozzle of the said patent and to equip 10 the automatic feeder thereof with auxiliary nozzles adapted to assist the central or main nozzle in winding the sheet and enable the entire front edge of the sheet to be positively gripped as it is moved slightly backwardly 15 and upwardly to form the loop and wind it. In feeding large sheets it has been found to be a great advantage to pick up the entire front edge of the sheet. This prevents the front edge from breaking and in some cases 20 from turning under as the sheet moves forwardly and also positively winds the sheet and performs the operation with greater certainty than when a sheet is lifted at a single point.

25 It is also an object of the invention to provide simple, practical and efficient means for creating vacuum in the auxiliary nozzles and for automatically discontinuing the vacuum in the said nozzles after the sheet has 30 been wound and started forwardly.

With these and other objects in view the invention consists in the construction and novel combination and arrangement of parts hereinafter fully described, illustrated in the 35 accompanying drawings and pointed out in the claims hereto appended, it being understood that various changes in the form, proportion and minor details of construction, within the scope of the claims, may be 40 resorted to without departing from the spirit or sacrificing any of the advantages of the invention.

In the drawings:

Figure 1 is a vertical sectional view of the 45 pick-up portion of an automatic feeder constructed in accordance with this invention.

Fig. 2 is a side elevation of the main suction nozzle.

Fig. 3 is a side elevation partly in section illustrating the construction of the auxiliary 50 suction nozzles.

Fig. 4 is a detail view of the bushing which forms the air-tight connection between the main suction nozzle and the main 55 suction hose.

Fig. 5 is a detail transverse sectional view of one of the auxiliary suction nozzles.

In the accompanying drawing in which is illustrated the preferred embodiment of the invention 1 designates the main suction 60 nozzle of the automatic pick-up mechanism. The main suction nozzle 1 which is substantially segmental or sector shaped is mounted on a transverse shaft 2 and is operated similar to the centrally arranged suction nozzle shown and described in the aforesaid patent 65 and has the mechanism for operating the shaft 2 both for rotating and swinging the same is similar to that shown and described in the aforesaid patent, and illustration of 70 the same in the present application is deemed unnecessary. The improved structure shown and described in the present application is designed to be applied to the 75 automatic feeder of the said patent and to be substituted for the suction nozzle shown and described therein. The main centrally arranged suction nozzle 1 is a double suction nozzle and is provided with an arcuate series of ports 3, 4, 5, 6, 7 and 8 but the 80 number of ports in the series may be varied as will be readily understood. Each of the suction ports of the series consists of a pair of passages arranged in parallelism as clearly illustrated in Fig. 1 of the drawings and the two passages of each suction port are connected at the top by a transverse passage having an outlet at one side of the double suction nozzle as clearly shown in Fig. 1 of the drawing. The transverse 85 connecting branch of the first suction port 3 of the double nozzle is indicated at 9 and the transverse connecting passages of the suction ports of the double suction nozzle are indicated at 10, 11, 12, 13 and 14 in 90 Fig. 2 of the drawings. The double suction

95

nozzle has an increased pick-up area by reason of the two sets of suction passages and the first suction port 3 of the double suction nozzle is connected by flexible hose 15 with auxiliary suction nozzles 16 mounted on the shaft 2 and rigid with the double suction nozzle and movable in unison with the same. The double suction nozzle 1 is tapped at 17 in line with the parallel passages of the first suction port 3 to receive short metallic tubes 18 preferably constructed of brass but any other suitable material may of course be employed and the said tubes 18 form convenient couplings or nipples for the connection of the inner ends of the hose sections 15 with the first suction port of the double suction nozzle. The hose sections 15 are preferably curved or arched as shown and their outer ends are connected by metallic tubes 19 with suction ports 20 of the auxiliary suction nozzles 16. The suction ports of the double nozzle are preferably of uniform diameter throughout the major portion of their length and are enlarged at the lower ends as shown and the auxiliary suction nozzles which have their ports 20 arranged in transverse alignment with the first suction port of the double suction nozzle are equipped at the lower ends of the ports 20 with yieldable suction cups 21 having enlarged lower portions and provided with tubular upper portions 22 which are fitted in the lower ends of the suction ports 20 of the auxiliary suction nozzles. The lower paper engaging peripheral edges of the suction nozzles are curved and the auxiliary nozzles have their curved edges recessed or cut away at 23 at the front ends of the said edges to receive the yieldable suction cups 21 which are adapted to pick up an uneven surface with greater facility than steel owing to the resiliency of the rubber cups. The metal sleeves 19 which are similar in construction to the metal sleeves 18 are tapped into the upper portions of the auxiliary nozzles at 24. The auxiliary and main nozzles are provided at the top with integral bearing sleeves or eyes 25 and 26 to receive the shaft 2 and they are adjustably secured to the said shaft by means of clamping or set screws 27 and 28 which will permit the ready adjustment of the auxiliary nozzles to arrange the same to suit the width of the sheets to be fed and when sheets are to be fed which are too narrow for the employment of the auxiliary nozzles detachable hose sections 15 may be removed from the auxiliary nozzles and one detached from the double suction nozzle. The other hose section may then be connected to the sleeve 18 from which the said hose section was removed. This will enable one of the hose sections to be doubled or arranged in substantially horse shoe shape for connecting the tubes 18 to

maintain the suction in the passages of the first suction port. The auxiliary nozzles may then be arranged out of the way by swinging them on the shaft and securing them in such out of the way position by the set screws 27. The auxiliary nozzles preferably consist each of a web portion flanged at the bottom to form a curved foot 29 and enlarged at the front portion at 30 to provide sufficient metal to contain the suction port 20 and to enable the metal tube 19 to be laterally offset from and clear the web or body portion of the auxiliary nozzles. Any suitable construction may of course be employed.

The double suction nozzle is provided at one side with a segmental enlargement 31 presenting a smooth flat bearing surface to a bushing 32 consisting of a wood bushing saturated with oil to form a suction contact member for connecting the main suction hose 33 with the double suction nozzle. The bushing 32 is provided with a central opening 34 and it fits against the segmental enlargement 31 and the opening 34 is adapted to register with the transverse passages of the suction ports and are successively brought into register with the same by the partial rotary movement of a double suction nozzle on the shaft 2. The vacuum will be maintained in each of the suction ports successively until the opening in the center of the bushing is carried away from each port. The bushing 32 is mounted on a metal sleeve 35 constructed of steel or other suitable material and provided with a port or passage 36 and having a metal tube 37 tapped into it at 38 for connection with the main suction hose 33. The sleeve 35 is provided with a reduced stem 39 and it is mounted in a bracket 40 having spaced arms 41 and 42 provided with openings for the reception of the sleeve and the stem 39. The stem receives a coiled spring 43 which is interposed between the arm 42 and the sleeve 35 for yieldably maintaining the bushing 32 in contact with the double suction bushing. The bracket is also provided with a slot 44 through which passes the metal tube 37 and which is of sufficient size to permit the necessary movement of the sleeve to maintain the bushing in proper contact with the double suction nozzle. The bracket is maintained in a fixed position with relation to the double suction nozzle and in practice will preferably be carried by the shaft of the said patent which carries the shaft on which the suction nozzle is mounted. The bracket may be mounted in any desired manner and partakes of all the movements of the double and auxiliary suction nozzles except the partial rotary movement of the same on the shaft 2 by which the ports are controlled.

The shaft 2 which carries the suction nozzles as explained in the aforesaid patent

moves downwardly to pick up a sheet from a stack. As it moves downwardly the suction valve of the automatic feeder closes the vent in the main suction line causing suction or vacuum in the first port 3 of the double suction nozzle and in the ports of the auxiliary suction nozzles. The vacuum holds the sheet while it is being lifted upwardly and slightly backwardly to form the loop and wind the sheet. The suction nozzles now rotate forwardly in accordance with the operation explained in the said patent and the vacuum in the first port will not be released until the edge of the port 15 opening of the bushing 32 as reaching the edge of the transverse passage of the said suction port at which point the vacuum will be broken. It will therefore be readily seen that the connection between the auxiliary nozzles and the main nozzles automatically 20 correctly times the pick up and release of the auxiliary nozzles without additional ports of mechanism.

What is claimed is:

25 1. In an automatic feeder of the class described, a double suction nozzle of approximately segmental shape having an arcuate series of suction ports, each port being provided with laterally spaced suction passages 30 extending to the periphery of the suction nozzle, and an auxiliary suction nozzle of approximately segmental form located at one side of and spaced laterally from the double suction nozzle and having a single 35 port connected with one of the suction ports of the double suction nozzle.

2. In an automatic feeder of the class described, a double suction nozzle of approximately segmental shape having an arcuate 40 series of suction ports, each port consisting of laterally spaced suction passages extending to the periphery of the nozzle and a transverse passage connecting the upper portions of the suction passages and extending 45 to the side face of the double suction nozzle, and auxiliary suction nozzles of approximately segmental form located at opposite sides of and spaced laterally from the double suction nozzle, each having a single suction 50 port, the suction ports of the auxiliary suction nozzles being connected with the laterally spaced suction passages of one of the ports of the double suction nozzle.

3. In an automatic feeder of the class 55 described, a double suction nozzle of approximately segmental shape having an arcuate series of suction ports, each port consisting of laterally spaced suction passages extending to the periphery of the nozzle and a 60 transverse passage connecting the upper portion of the suction passages and extending to the side face of the double suction nozzle, said double suction nozzle presenting a smooth surface at such side face and 65 means for connecting the suction ports with

a suction hose, said means having a member yieldably engaging the said smooth side face of the suction nozzle and adapted to communicate successively with the said series of ports, and auxiliary suction nozzles of approximately segmental form located at opposite sides of and spaced laterally from the double suction nozzle, each having a single suction port, the suction ports of the auxiliary suction nozzles being connected with the laterally spaced suction passages of one of the ports of the double suction nozzle. 75

4. In an automatic feeder of the class described, a double suction nozzle of approximately segmental shape having an arcuate 80 series of suction ports, each port consisting of laterally spaced suction passages extending to the periphery of the nozzle and a transverse passage connecting the upper portion of the suction passages and extending 85 to the side face of the double suction nozzle, said suction nozzle being provided with an arcuate enlargement presenting a smooth side face and means for connecting the suction nozzle with a suction hose, said means 90 having a spring pressed member fitting against the said enlargement and provided with a passage adapted to be carried successively into communication with the series of suction ports, and an auxiliary suction 95 nozzle of approximately segmental form located at one side of and spaced laterally from the double suction nozzle and having a single port connected with one of the suction 100 ports of the double suction nozzle.

5. In an automatic feeder of the class described, a substantially segmental suction nozzle having an arcuate series of ports provided with laterally extending passages, means for connecting the suction nozzle with 105 a suction hose, said means comprising a yieldably mounted member consisting of a sleeve having a passage and provided with a suction member fitting in said sleeve and having an enlarged head fitting against the side of the suction nozzle and having an opening adapted to communicate successively with the suction ports of the said nozzle.

6. In an automatic feeder of the class described, a substantially segmental suction 110 nozzle having an arcuate series of ports provided with laterally extending passages, means for connecting the suction nozzle with a suction hose, said means comprising a relatively fixed bracket having spaced portions, 115 a sleeve guided in one of the portions and provided with a stem slidably mounted in the other of the said portions, said sleeve being provided with a passage, a spring mounted on the stem and engaging the bracket and the sleeve for urging the stem towards the suction nozzle, means carried 120 by the sleeve for fitting against the nozzle to form an air-tight connection therewith and a tubular member mounted on the sleeve 125 130

and communicating with the passage thereof and slidably in the bracket for coupling the suction hose to the sleeve.

7. In an automatic feeder of the class described, a substantially segmental suction nozzle having an arcuate series of ports provided with laterally extending passages, means for connecting the suction nozzle with a suction hose, said means comprising a relatively fixed bracket having spaced portions, a sleeve guided in one of the portions and provided with a stem slidably mounted in the other of the said portions, said sleeve being provided with a passage, a spring mounted on the stem and engaging the bracket and the sleeve for urging the stem towards the suction nozzle, means carried by the sleeve for fitting against the nozzle to form an air-tight connection therewith, said means including a yieldably mounted tubular member and a head carried by the said member and fitted against the suction nozzle and consisting of an absorbent material saturated with a lubricant.

23. 8. In an automatic feeder of the class described, a substantially segmental suction nozzle having an arcuate series of ports provided with laterally extending passages, means for connecting the suction nozzle with a suction hose, said means comprising a relatively fixed bracket having spaced portions, a sleeve guided in one of the portions and provided with a stem slidably mounted in the other of the said portions, said sleeve being provided with a passage, a spring mounted on the stem and engaging the bracket and the sleeve for urging the stem toward the suction nozzle, means carried by the sleeve for fitting against the nozzle to form an air-tight connection therewith, said means including a bracket, a sleeve slidably mounted in the bracket and provided with a passage, a tubular member mounted on the sleeve and forming a coupling for connecting the stem with the suction hose, a wooden bushing carried by the sleeve and fitting against the suction nozzle to form an air-tight connection and a spring for yieldably maintaining the sleeve in engagement with the suction nozzle.

9. In an automatic feeder of the class described, a main segmental suction nozzle provided with a series of separate suction ports, approximately segmental auxiliary suction nozzles having a single suction port connected with one of the suction ports of the main suction nozzle and means for successively connecting the ports of the main suction nozzle with a suction hose whereby the auxiliary suction nozzles will be automatically cut off from the suction hose when the said means is carried out of communication with the port to which the auxiliary suction nozzle is connected.

65. 10. An automatic feeder of the class de-

scribed, a main suction nozzle having a series of suction ports, an approximately segmental auxiliary suction nozzle having a single suction port located at the front of the auxiliary suction nozzle and connected with one of the suction ports of the main suction nozzle, said auxiliary suction nozzle having a curved paper supporting face extending in rear of the said single suction nozzle, and means for successively connecting the ports of the main suction nozzle with a suction hose, said auxiliary suction nozzle being automatically cut off from the suction hose when the suction port of the main suction nozzle to which it is connected is carried out of communication with the suction hose.

11. In an automatic feeder of the class described, a main double suction nozzle provided with a series of suction ports each having a pair of suction passages extending to the periphery of the suction nozzle, auxiliary suction nozzles connected with one of the ports of the double suction nozzle and means for successively connecting the suction hose with the ports of the double suction nozzle.

12. In an automatic feeder of the class described, a main double suction nozzle provided with a series of suction ports, auxiliary suction nozzles located at opposite sides of the main suction nozzle in spaced relation with the same and each having a single suction port, removable hose sections detachably coupled to the double suction nozzle and the auxiliary suction nozzles, and connecting the single suction port of both auxiliary suction nozzles with one of the suction ports of the double suction nozzle, and means for successively connecting the suction ports of the double suction nozzle with a suction hose.

13. In an automatic feeder of the class described, a suction nozzle having a series of suction ports, means for successively connecting the ports with a suction hose, auxiliary suction nozzles, a pair of nipples carried by the main suction nozzle and communicating with one of the ports thereof, auxiliary suction nozzles each provided with a single port and having a projecting nipple communicating therewith and hose sections connecting the nipples of the auxiliary suction nozzles with the main suction nozzles, said hose sections being detachable and the nipples of the main suction nozzle being adapted to be connected by one of the hose sections when the latter are removed from the auxiliary nozzles.

14. In an automatic feeder of the class described, a main suction nozzle having a series of suction ports and an auxiliary suction nozzle having a single port connected with one of the ports of the main suction nozzle, said auxiliary suction nozzle being provided at its periphery with a yieldable sheet engaging cup and having a curved paper supporting face extending rearwardly from a

point adjacent the said single port of the auxiliary suction nozzle.

15. In an automatic feeder of the class described, a main suction nozzle and an auxiliary suction nozzle having a single port connected with the main suction nozzle, said auxiliary nozzle being provided at its per-

iphery with a recess and having a yieldable suction cup mounted in the suction port and provided with a sheet engaging head projecting in rear of the said recess. 10

In testimony whereof I affix my signature.

LESTER KYLE ALDRICH.
